UNITED STATES PATENT OFFICE.

SAMUEL M. VAUCLAIN, OF PHILADELPHIA, PENNSYLVANIA, ASSIGNOR TO BURNHAM, WILLIAMS & COMPANY, OF PHILADELPHIA, PENNSYLVANIA, A FIRM.

ARTICULATED LOCOMOTIVE.

No. 918,401.

Specification of Letters Patent. Patented April 13, 1909.

Application filed December 12, 1908. Serial No. 467,184.

To all whom it may concern:

Be it known that I, SAMUEL M. VAUCLAIN, a citizen of the United States, residing in Philadelphia, Pennsylvania, have invented 5 certain Improvements in Articulated Locomotives, of which the following is a specification.

The object of my invention is to provide a superheater for a locomotive of the type 10 known as an "articulated compound", in which there are two frames, one frame being pivoted to the other; the high pressure cylinders being mounted on one frame and the low pressure cylinders being mounted 15 on the other frame. The boiler is rigidly mounted on the rear frame and overhangs the forward frame.

By my invention I am enabled to mount the superheater in the smoke box at the forward end of the boiler and connect it with 20 the two sets of cylinders.

In the accompanying drawings:—Figure 1, is a wide view, partly in section, of sufficient of an articulated compound locomotive 25 to illustrate my invention; Fig. 2, is a transverse sectional view on the line 2—2, Fig. 1; and Fig. 3, is a transverse sectional view on the line 3—3, Fig. 1.

A is the rear frame of the locomotive and 30 A' is the forward frame, each having boxes for the axles of the driving wheels a, a', respectively. The two frames are pivoted together at a² by any suitable connection.

B, B are the high pressure cylinders rigidly mounted on the frame A, and C, C are the low pressure cylinders rigidly mounted 35 on the frame A'. The high pressure cylinders B are connected by live steam pipes b to the steam dome d' of the boiler D; this 40 boiler is mounted rigidly on the rear frame A and swings with it. The front end of the boiler overhangs the forward frame and has one or more saddles d² which are arranged to slide upon supports a³ carried by the said 45 frame, so that the boiler is free to move radially over the forward frame in turning curves.

d is the smoke box at the forward end of the boiler and in this smoke box is mounted 50 the superheater E of any form desired, providing it does not interfere with the internal arrangement of the smoke box.

The superheater shown in the drawings 55 consists of two headers e, e' at the lower end and two headers e², e² at the upper end,

and connected together by a pipe e³; curved pipes e⁴ are arranged on each side of the smoke box and connect the upper and lower headers. One lower header is connected to the exhaust passage of the high pressure 60 cylinders and the other lower header is connected to the steam inlet passage of the low pressure cylinders.

F is a transverse pipe coupled at each end to the exhaust passage b' of the high pressure 65 cylinders B.

G is a fitting, in the present instance so shaped as to provide two passages g, g', as shown in the drawings. A longitudinal pipe F' is coupled to the transverse pipe F and 70 communicates with the passage g of the fitting; the upper end of the passage g communicates with a longitudinal pipe H coupled at its forward end to the header e of the superheater. The connections alluded 75 to are all rigid, as the superheater is mounted in the smoke box of the boiler which is rigidly secured to the frame A on which the cylinders B are mounted, but the connections between the superheater and the 80 cylinders on the frame A' must be flexible.

I is a pipe leading from the header e' of the superheater rearwardly and communicates with the passage g' in the fitting G. The fitting in the present instance is so 85 shaped that the pipe H is on one side of the boiler and the pipe I is on the opposite side, but the arrangement of pipes may be modified, depending upon the general arrangement of the elements of the locomotive 90 and the position of the superheater carried by the boiler. The passage g' in the fitting G terminates in a socket g², and mounted in this socket is the end of a pipe K, the other end of the pipe being mounted in a socket 95 m of a yoke fitting M which is coupled to pipes m', m' leading to the steam supply passage of the low pressure cylinders C, C on the frame A'. In the present instance the pipe K is made in three parts k, k', k². 100 The central part k being adapted to slide in a packed section k³ which is coupled to the part k' having an upturned portion k⁴ adapted to the packed socket g². The upturned portion has a ring k⁵ which holds it 105 in position and yet allows it freedom to swing in the socket. The part k² of the pipe K is at the opposite end and is similar in form to the part k' and adapted to the packed socket m of the yoke fitting M. The 110

part k^2 also has a ring k^6 to hold it in place and allow it to freely swing.

It will be understood that while I have shown a particular arrangement of pipes leading from the cylinders on one frame to the superheater in the smoke box and from the superheater to the cylinders on the other frame, the arrangement of pipes may be modified without departing from my invention, which is to mount the superheater in the overhanging boiler section and connect it to the two sets of cylinders of a locomotive of the articulated type.

The exhaust for the low pressure cylinders is carried to the nozzle d^3 in the smoke box, in the present instance through a jointed pipe C' .

It will be seen that by the above arrangement the steam enters the high pressure cylinders B , B direct from the dome of the boiler, then passes from the cylinders through the rigidly connected pipes to the superheater E situated in the present instance in the smoke box at the forward end of the boiler, and after passing through the superheater the steam flows through the flexibly coupled pipes leading to the low pressure cylinders on the forward frame and from these cylinders through the flexible coupling to the exhaust nozzle in the smoke box of the boiler.

I claim:—

1. The combination in a locomotive of

the articulated type, of rear and forward frames coupled together, a boiler rigidly mounted on one frame and overhanging the other frame, a superheater carried by the boiler, a cylinder on the frame overhung by the boiler, and a flexible connection between the superheater and the cylinder.

2. The combination in a locomotive of the articulated type, of rear and forward frames, a boiler rigidly mounted on the rear frame and overhanging the forward frame, a cylinder on the forward frame, a superheater carried by the boiler, and a flexible connection between the superheater and the cylinder.

3. The combination in a locomotive of the articulated type, of a rear frame and a forward frame pivoted together, a boiler rigidly mounted on the rear frame, a high pressure cylinder mounted on the rear frame, a low pressure cylinder mounted on the forward frame, a superheater carried by the boiler, a connection between the high pressure cylinder and the superheater, and a flexible connection between the superheater and the low pressure cylinder.

In testimony whereof, I have signed my name to this specification, in the presence of two subscribing witnesses.

SAMUEL M. VAUCLAIN.
